Inventor:

John J. Lynch

UNITED STATES PATENT OFFICE.

JOHN J. LYNCH, OF WASHINGTON, DISTRICT OF COLUMBIA, ASSIGNOR TO
MARY LOUISA LYNCH, OF SAME PLACE.

DESIGN FOR BELLS.

Specification forming part of Design No. 9,589, dated October 10, 1876; application filed October 14, 1875.
[Term of Patent 3½ years.]

To all whom it may concern:

Be it known that I, JOHN J. LYNCH, of Washington, in the county of Washington, and in the District of Columbia, have invented a certain new and original Design for Hand-Bells; and do hereby declare that the following is a full, clear, and exact description thereof, reference being had to the accompanying drawing, making a part of this specification.

The distinctive feature of my design consists in a bell, A, which has the form and configuration of the old "Independence Bell," and is surmounted by a figure, B, which rep-

resents the Goddess of Liberty, and has such relative size and proportion as to render it suitable for a handle.

Having thus described my invention, what I claim as new is—

The design for a bell, substantially as shown. In testimony that I claim the foregoing I have hereunto set my hand this 13th day of October, 1875.

JOHN J. LYNCH.
